UNITED STATES PATENT OFFICE.

STAFFORD F. SUTHERLAND, OF PHILADELPHIA, PENNSYLVANIA, ASSIGNOR TO SUTHERLAND COLLAPSIBLE PAPER BOX COMPANY, OF PHILADELPHIA, PENNSYLVANIA, A CORPORATION OF DELAWARE.

COLLAPSIBLE FOLDING BOX.

Application filed May 17, 1921. Serial No. 470,328.

REISSUED

To all whom it may concern:

Be it known that I, STAFFORD F. SUTHERLAND, a citizen of the United States, residing at the city and county of Philadelphia and State of Pennsylvania, have invented certain new and useful Improvements in Collapsible Folding Boxes, of which the following is a specification.

My invention relates to folding-boxes and especially to that type known as collapsible boxes and the object of my invention is to provide an improved box of this character, that is simple in construction, inexpensive of manufacture, and can be very easily and very quickly set up (erected in box form) and is securely held in erect position after it is set up, and also presents a very neat appearance.

Another object of my invention is to provide a collapsible folding box, that may be made of cheap box-board (such as is now used in the making of what is known as set-up boxes, boxes that are made set-up or erect and are not collapsible) and covered or partly covered with paper or other suitable material.

The objects and advantages of my improved box will be readily apparent in this specification when taken in connection with the accompanying drawings, in which—Fig. 1 is the blank of the box; Fig. 2 is a facing-strip; Fig. 3 shows facing-strips attached to opposite ends of the blank; Fig. 4 shows the opposite side-walls of the box folded inwardly; Fig. 5 is a reinforcing-strip; Fig. 6 shows reinforcing-strips attached to the paper flaps; Fig. 7 shows the complete box with the flaps folded inwardly on the box; Fig. 8 is a covering-strip; Figs. 9 and 10 show covering-strips attached to opposite side-walls of the box; Fig. 12 is a facing-strip; Figs. 11 and 13 show facing-strips (Fig. 12) attached to opposite end-walls of the box; Fig. 14 is a holding-flap; Figs. 15 and 16 show the complete box with holding-flaps attached; Fig. 17 is a blank of the box cover; Fig. 18 shows this blank covered with paper; Fig. 19 shows opposite side-walls of the cover folded inwardly; Figs. 20 and 21 show the complete box-cover with holding-flaps attached. Fig. 22 is a perspective of the box partly set up. Fig. 23 is a perspective of the box fully set

up, and Fig. 24 is a perspective of the box and its cover.

Referring to the drawings, Fig. 1 is the blank of which the box is formed, and is a single piece of paper-board or other suitable material, and it is scored or creased longitudinally at the dotted lines 2 and 55 transversely at the dotted lines 3, so as to facilitate the bending or folding of its various parts at these lines, in forming the box and this blank comprises the following foldable parts, a bottom A, opposite side-walls B integrally connected with the bottom, opposite end-walls C integrally connected with the bottom and triangular corner-flaps D integrally connected with the side-walls. A strip of paper or other 60 suitable light material (Fig. 2) and which I will call the facing-strip E, is gummed to the outer face of each end-wall C and the adjacent triangular corner-flaps D, as shown in Fig. 3, and it will be seen that 65 this facing-strip extends across the blank and covers the end-wall and both triangular corner-flaps and connects them, and it also extends outwardly beyond the edge 4 of the end-wall, and the object of which will be 70 presently understood. The side-walls B and the corner-flaps are then folded inwardly on the blank as shown in Fig. 4, and a strip of heavy paper or light box-board (Fig. 5) and which I will call the 75 reinforcing-strip F is gummed to the part 5 of the facing-strip E that projects outwardly beyond each end-wall, as shown in Fig. 6, and thus forming a flap which I will call the holding-flap G and which holds the 80 box in an upright position when it is set up. In this set-up condition of the box the end edges of the holding or locking flaps G frictionally engage the side walls or members of the box and are thus held in locking position. Fig. 7 is the complete box, 85 in its flat or collapsed form, with the holding flaps G folded on the box.

When it is desired to have all the walls of the box covered, this may be done in 90 the following manner—a strip of paper (Fig. 8) which I will call the covering-strip H, is pasted to the outer face of each side-wall B with the lower edge 6 of the paper pasted to the bottom of the box and its 95 upper edge 7 turned over and pasted to

the inner face of the wall, as shown in Fig. 9, and the projecting ends 8 of the covering-strip are turned in and pasted down, as shown in Fig. 10. The side-walls 5 and corner-flaps are then folded inwardly on the blank, as shown in Fig. 11, and a facing-strip E^1 (Fig. 12) is pasted on the outer face of each end-wall and projects outwardly beyond the outer edge of the end- 10 wall, as shown in Figs. 11 and 13. In Fig. 11, the front, and in Fig. 13 the back, of the box is shown, with the facing-strip attached. A holding-flap G^1 (Fig. 14) that is creased, scored or slit at the dotted line 15 9, is attached to each end of the box as shown in Fig. 15; the part 10 of this flap is inserted between the inner face of the end-wall and the inturned parts 8 of the facing-strip and is gummed to these in- 20 turned parts, and the projecting part 11 of the facing-strip is gummed to the flap. Fig. 16 shows the holding-flap G^1 folded inwardly on the box. Fig. 17 is the blank of the box-cover which is practically the same 25 as the blank Fig. 1, of the box, and this blank is entirely covered on its outer face by a paper sheet as shown in Fig. 18 and which I will call the covering-sheet J . Opposite projecting edges 12 of this covering- 30 sheet are turned over the outer edges of the side-walls B^1 and pasted on their inner faces, and the ends 13 of the sheet extend outwardly beyond the outer edges 14 of the end-walls C^1 . The side-walls and 35 triangular flaps D^1 are then folded inwardly on the blank as shown in Fig. 19 and a holding-flap G^2 attached to each end, as shown in Fig. 20. Fig. 21, shows the complete box-cover with the holding-flaps 40 folded inwardly on the cover. It is of course obvious that the box may be covered in the same manner as its cover, or the cover may be covered in the same manner as the box. In setting up (erecting) the box or its 45 cover, from its flat form, it is only necessary to grasp both end-walls and push them to an erect position and the side-walls will automatically move to an erect position also; the other movable parts automatically 50 moving to their respective positions, the

holding-flap moving downward in the interior of the box, and against the inner face of the corner-folds and the end-wall.

Fig. 22 shows the box partly set up,

Fig. 23 the box fully set up, and

Fig. 24 the box with its cover on it.

55

Having fully described my invention, what I claim as new, and desire to secure by Letters Patent is:

1. A collapsible box including integral 60 bottom, side and end walls, triangular corner flaps on the side walls, a facing strip secured to the end walls, and a locking flap secured to the facing strip.

2. A collapsible box including foldable 65 side and end walls, corner flaps on said side walls, a facing strip secured to the side and end walls, and corner flaps and a locking flap secured to said facing strip.

3. A collapsible box including foldable 70 side and end walls, flexible means secured to the side and end walls, and a locking flap secured to the flexible means.

4. A collapsible box including foldable 75 side and end walls, corner flaps on said side walls, flexible means connecting said corner flaps and end walls, and a locking flap secured to said flexible means.

5. In a collapsible box having foldable 80 side and end walls, a facing strip secured to the side walls and an end wall, and a locking flap secured to the facing strip.

6. In a collapsible box having foldable 85 side and end walls, a facing strip secured to the side walls and an end wall, and a locking flap secured to the facing strip, said locking flap being of substantially the same depth as the end wall.

7. In a collapsible box having foldable 90 side and end walls, corner flaps on the side walls, a facing strip connecting a pair of the corner flaps and an end wall, and a locking flap secured to the facing strip.

8. In a collapsible box having foldable 95 side and end walls, a facing strip secured to the side walls and an end wall, and a locking flap secured to said facing strip, the facing strip adapted to form corner folds.

STAFFORD F. SUTHERLAND.
